UNITED STATES PATENT OFFICE.

PHILIP A. STEPHENS, OF ST. LOUIS, MISSOURI.

TORPEDO-GUARD.

1,257,757.

Specification of Letters Patent. Patented Feb. 26, 1918.

Application filed June 9, 1917. Serial No. 173,757.

To all whom it may concern:

Be it known that I, PHILIP A. STEPHENS, a citizen of the United States, residing at the city of St. Louis and State of Missouri, have 5 invented a new and useful Torpedo-Guard, of which the following is a specification.

This invention relates to improvements in torpedo-guards and consists in the novel construction hereinafter disclosed.

10 An object of the invention is to provide an efficient guard for deflecting an approaching torpedo from its path so as to prevent the same from striking the hull of the vessel.

Another object of the invention is to provide 15 a guard for deflecting a torpedo which may be readily attached to vessels and which may be held in protecting position while the vessel is under way without substantially retarding the progress of the vessel through

20 the water.

Another object of the invention is to provide 25 a guard comprising a plurality of vertically suspended strands having an engaging surface for contacting with the body of the torpedo as the same approaches the hull of the vessel and thereby deflect the torpedo from its path.

With the foregoing and other advantages 30 attainable from the construction of the present invention in view, I have produced the construction hereinafter fully described, reference being made to the accompanying drawing, in which—

Figure 1 is a plan view of a vessel having 35 the guard of the invention applied thereto.

Fig. 2 is a side elevation of a vessel showing the manner in which the guard is applied thereto.

Fig. 3 is a detailed view of a part of the 40 supporting means for sustaining the guard in position upon the vessel.

Fig. 4 is a detailed view in vertical section of the preferred form of strand used in the construction of the guard.

45 Fig. 5 is a cross section of the same element on the line 5—5 of Fig. 4.

In the embodiment of the invention illustrated in the drawing the support for the guard comprises a series of arms 1 pivoted 50 at suitable intervals along the side of the vessel to brackets 2. The arms 1 are formed with hooked sections 3 at their outer extremities having eyes 4 above the hooked sections in which are engaged rings 5 of flexible connections 6. The flexible connections 6 at their inner ends are wound upon a drum 7

of a windlass construction 8. Depending from each of said arms is a vertical strand or cable 9. The upper ends of the cables 9 have hooks 10 which fit over the arms 1. Thus 60 when the arms 1 are raised by the windlass construction the hooks 10 will slide backwardly on the arms carrying the entire guard inwardly toward the hull of the vessel.

Connected with and supported by the 65 upper ends of the cables 9 is a longitudinal cable 11, and near the bottom of the cables 9 and connected therewith is a longitudinal cable 12. Intermediate of the cables 11 and 12 is a longitudinal cable 13, it being understood 70 that other longitudinal cables may be provided in order to give additional strength to the guard if desired. Extending vertically and disposed at considerable intervals are a series of vertical cables 14, said 75 cables 14 being supported at their upper ends by the longitudinal cable 11 and at their lower ends by the longitudinal cable 12. It is the purpose to support at either side of the vessel a guard constructed substantially as described, the same being disposed in the manner illustrated in the drawing thus protecting both sides of the hull of the vessel.

The intervals or spaces between the strands 80 14 are of substantial width so that a torpedo approaching the hull of the vessel may freely enter between any pair of the vertical strands. As it is contemplated that the guard shall be used when the vessel is under 90 way, it is obvious that before the entire length of the torpedo passes between adjacent ones of the cables 14 it will be overtaken by the forward one of said cables and deflected from its course as indicated in Fig. 95 1, the nose of the torpedo being thrown outwardly and away from the vessel. As the strands are disposed at considerable intervals the guard does not present any impact surface against which the torpedo may 100 strike, the strands merely serving as actuating means for turning the torpedo from its path.

In order to hold the guard in proper relation to the ship's hull a series of weights 105 15 are attached to the lower end of the guard at considerable intervals. In order to prevent the backward sweep of the guard at the prow of the vessel an outwardly projecting arm 16 is provided. Stay wires 17 extend 110 from the outer end of said arm 16 to the lower part of the guard structure proper. A

similar arm 18 with similarly attached stay wires 19 may also be provided at the stern of the vessel. Stay wires 17 and 19 together with the weights 20 serve to hold the guard structure at a distance from the hull of the vessel and to a depth sufficient to guard the entire depth of the hull.

The preferred design of the cables of which the guard is constructed is illustrated in Figs. 4 and 5. The core 21 of the cables is of wound wire rope covered by a coating 22 of rubber. When the cable impacts against the body of the torpedo 23 the rubber covering will tend to bind against the surface and thereby draw the nose of the torpedo out of its path into alignment with the path of the vessel.

I am aware that the principles of the invention may be embodied in other and additional forms, and I do not limit myself therefore to the exact details as shown and described, but what I claim and desire to secure by Letters Patent, is:—

1. A torpedo guard, comprising suspending arms pivoted to the hull of a vessel and extending outwardly therefrom, means for raising and lowering said arms, a supporting strand extending longitudinally of the vessel and carried by said arms, a plurality of spaced vertical strands extending from said supporting strand, the space between said vertical strands being in excess of the width of a torpedo, thereby permitting a torpedo to pass entirely therebetween, and means for holding the strands in position about the hull of the vessel.

2. A torpedo guard, comprising a series of longitudinal and vertical strands of cable attached together, the space between the

vertical strands being sufficient to receive the entire body of a torpedo therebetween, supporting means whereby said guard is supported at the side of the vessel, weights attached to the bottom of said guard for holding the same in substantially a vertical position, and an arm extending from the bow of the vessel and having stay wires attached to the outer end thereof and to the bottom of said guard.

3. A torpedo guard, comprising a series of longitudinal strands and a series of vertical strands connected together and so constructed as to entirely receive a torpedo between the vertical strands, means for supporting said guard by the vessel, and means for holding the guard in substantially vertical position.

4. In a torpedo guard, the combination with arms pivoted to the vessel and extending outwardly from the side thereof, a guard composed of longitudinal and vertical strands of cable, the vertical strands being spaced a considerable distance apart to receive the entire body of a torpedo therebetween, rings attached to the arms and slidably thereon supporting said guard whereby said guard is extended outwardly from the vessel when the arms are in one position and moved inwardly toward the vessel when the arms are raised to another position, and means for raising and lowering said arms.

5. The combination with the hull of a vessel, of a guard composed of a net, the interstices of which are of such a size as to permit a torpedo to pass entirely therethrough, and means for supporting said net at a distance from the hull of the vessel.

PHILIP A. STEPHENS.
